UNITED STATES PATENT OFFICE.

CECIL P. BRADLEY, OF NAPOLEON, OHIO.

SWITCH MECHANISM.

Application filed March 25, 1926. Serial No. 97,318.

This invention relates to switch constructions which are particularly adapted for use in electric light sockets, wall boxes, chandeliers, or other forms of electric fixtures for controlling one or a plurality of lamps through the operation of a single pull chain or push button.

An object of the invention resides in providing a switch mechanism which is operable to control a plurality of electric lights such as used in chandeliers or other forms of electric fixtures for controlling a plurality of lights by the operation of a single pull chain or push button so that one or more of the lamps may be placed in circuit and lighted or all extinguished in a predetermined manner by the operation of the switch thru the successive operation of the pull chain or push button.

A further object of the invention resides in providing a switch construction for devices of the type above mentioned in which a plurality of stationary contacts are constructed in duplicate form and removably attached to a suitable base member which mounts a movable contact member including a ratchet mechanism formed with sets of contact surfaces adapted to cooperate with the stationary contacts to control the circuit to the lamps in a predetermined manner in accordance with the step by step rotation of the movable contact element.

The invention incorporates numerous other objects and features in the details of construction and the arrangement of parts which are more particularly pointed out in the following detailed description and in the claims directed to a preferred form of the invention, it being understood, however, that various changes in the size, shape and arrangement of these parts may be made without departing from the spirit or scope of the invention as herein set forth.

In the drawings forming part of this application:

Figure 1 is a plan view of a switch construction made in accordance with this invention shown on a substantially enlarged scale.

Fig. 2 is an end elevation of the switch structure shown in Fig. 1.

Fig. 3 is a vertical sectional view taken on line 3-3 of Fig. 1.

Fig. 4 is a sectional view taken on the line 4-4 of Fig. 1.

Fig. 5 is a sectional view taken on the line 5-5 of Fig. 1.

Fig. 6 is a plan view of a slightly modified form of structure.

Fig. 7 is a sectional view taken on line 7-7 of Fig. 6.

Fig. 8 is a sectional view taken on line 8-8 of Fig. 6.

Fig. 9 is a bottom plan view of another switch construction embodying the principles of this invention.

Fig. 10 is a sectional view taken on line 10-10 of Fig. 9.

Fig. 11 is a top plan view of the switch construction shown in Fig. 9.

Fig. 12 is a transverse sectional view thru the stationary contact structure of the switch shown in Fig. 9, illustrating the arrangement of the stationary contacts for cooperation with the rotatable contact member.

A base plate is indicated at 1 at the opposite ends of which are mounted a pair of bearing brackets 2 in which is rotatably mounted the shaft 3. The rotatable contact member 4 in the form of a hollow cylinder is provided with closed ends as indicated at 5 which are mounted on the shaft 3 for rotation therewith, the central portion of the body of the cylinder between the ends being formed in the cut out portion 6 having a plurality of circumferentially spaced shoulders 7 arranged in stepped relation as clearly illustrated in Figs. 1 and 5 of the drawings.

The left hand end of the cylindrical contact member 4 is formed to provide a plurality of ratchet teeth 8 arranged in the same axial plane as the shoulder 7 of the cut out portion 6 in order that the resilient pawl 9 mounted on the base 1 will cooperate with the shoulders 8 of the ratchet teeth formed on the cylindrical contact member and prevents the same from rotating in one direction. The opposite end of the cylindrical contact member 4 is formed with a plurality of beveled projections 10 extending laterally from the end wall 5 thereof to provide another series of teeth adapted for cooperation with the operating device 11 on the rotatable operating member 12.

This operating member 12 is rotatably mounted on the shaft 3 and is normally rotated in one direction by the operation of the coiled spring 13 surrounding the shaft 11.

3 and having one end anchored in the member 12 and the opposite end anchored in the bracket 2, carried by the base. This member 12 is provided with an operating handle 14, extending through the guide 15 mounted on the base which is adapted to limit the stroke of movement of the handle 14 and the stroke or amount of rotation of the member 12. In this way, the handle 14 is adapted to be moved through a stroke of operation governed by the guide 15 which will produce a cooperation between the operating member and the feet 10 on the check member so as to rotate the cylindrical contact member one step for each cycle of operation in the operating member 14.

The resilient stationary pawl 9 cooperates with the ratchet teeth 8 on the cylinder 4 to prevent reverse rotation after one step of movement through the operation of the lever 14. In this way, the cylinder is rotated in a step by step movement for each reciprocation of the lever 14 so that the step shoulders 7 will successively engage with the respective stationary contact strips 16 for energizing or de-energizing the respective circuits connected with said stationary contacts.

These stationary contacts 16 are formed of resilient strip material having laterally extending end portions 17 extending upwardly and adapted for resilient engagement with the periphery of the contact cylinder 4 so that in the rotation thereof the cylinder through the provision of the recess 6 and the shoulder construction 7 will successively engage predetermined of these resilient contacts 16 for closing the control circuit in a predetermined manner. These stationary contacts 16 are received in grooves 18 formed in a mounting block 19 which is suitably secured to the base member 1 for obtaining the stationary contact 16 in rigid relation on the base member.

This construction permits the ready assembly and adjustment of the stationary contacts for proper cooperation with the periphery of the rotatable contact cylinder 4, the securing element 20 serving to rigidly lock the stationary contact member 16 in position on the base 1 when operated to tightly secure the block member 19 thereto.

The cylinder structure forms a particular feature of this construction in which the opposite ends are closed and formed with ratchet teeth for cooperation with the pawl 9 and the operating member 12, while the central portion is hollow and cut away to provide the controlling contact shoulders adapted for engagement and circuit closing cooperation with the stationary contacts on the base.

In Figs. 6 to 8 inclusive, a substantially similar construction is shown which includes a base 21 on which is mounted a pair of

bearing brackets 22 in alined relation rotatably mounting the shaft 23 carrying the rotatable contact body 24. This contact body 24 is of cylindrical structure having a plurality of arcuate annular projections 25 formed in spaced relation lengthwise of the body thereof. These projections 25 are of unequal length and have one end of each projection terminating in the same axial plane as indicated at 26 in Fig. 8, while the opposite ends terminate in stepped relation circumferentially, as is illustrated at 29 in Fig. 8, and are beveled for a purpose which will presently appear.

One end of the body, as shown at the left hand end of Figs. 6 and 7 is formed with an annular flange 30 formed to provide a number of ratchet teeth corresponding with the number of points 29 at which the arcuate projections 25 terminate, so that the body may be retained against reverse rotation after each successive stepped operation thereof. For this purpose a resilient stationary pawl 31 cooperates with the ratchet teeth of the flange 30 in retaining the body against rotation in one direction.

The opposite end of the body 24 is formed to provide ratchet teeth 32 as shown clearly in Fig. 6, with which cooperates the operating member 33 slidably and rotatably mounted on the shaft 23 and formed with ratchet teeth 34. The coiled spring 35 is mounted on the shaft 23 and has one end anchored in the bearing bracket 22 while the opposite end is secured to the operating member 33 and normally serves to rotate it in one direction, so that the operating lever 36 extending through the guide bracket 37 limits the rotative movement of the operating member under the action of the spring. This guide bracket 37 also limits the rotative movement under the operation of the lever 36 so that it will be moved to one step of movement for rotating the body 24 a step of movement for each operation of the operating member 33 and the lever 36.

A block member 38 is mounted on the base member or plate in spaced parallel relation to the body 24 and is formed with a plurality of slots 39 extending transversely across the face of the body member disposed toward the body 24 and in alined relation with the arcuate projecting flanges 25 to form guides for resilient contact terminals 40 of the contact members 41. These contact members are of substantially U-shape in construction as illustrated clearly in Fig. 8, and have the portions 42 joining the legs seated in grooves 43 formed in the face of the block adjacent the base plate and the end opposite the resilient contact portions 40 seated in grooves 44 and retained therein by the securing plates 45 secured to the block 38 by suitable means indicated at 42.

As the operating lever 36 is operated through each stroke of movement, it will be seen that one of the annular flanges 25 will be successively engaged with the corresponding contact end 40 of the contact members so as to successively close the circuit connected therewith, a common circuit from the source of power being attached to one of the bearing brackets 22 so that the body 10 24 forms a movable contact member of the switch mechanism. The block member 38 and the securing plate 45 serve to rigidly mount the contact members on the base plate and to provide guides for the ends 40 to 15 permit the free movement thereof under the operation of the flanges 25 so that efficient contact will be constantly insured. A pull chain or push button structure may be connected to the operating lever 36 and extended through any housing structure for the switch member to entirely enclose the same so that the operation of either the switch button or pull chain as the case may be, can be utilized to produce the stroke of 20 movement of the operating lever 36 for rotating the body 24 through a step by step motion.

Figs. 9 to 12 show that the same idea is carried out with a slightly different form 30 of switch construction wherein the base plate 47 mounts the shaft 48 which extends laterally therefrom and is positioned in the center to rotatably support the movable contact plate 49 adapted for rotation thereon which has its periphery cut away in stepped relation as indicated at 50 to provide a plurality of shoulders 51 in spaced circumferential relation. The central portion of 35 the contact plate 49 is formed with ratchet teeth 52 with which cooperates the teeth 53 of the operating member 54, which carries the arm 55 extending laterally therefrom in spaced parallel relation with the base 47 for receiving a suitable pull chain 40 56 or the like, by which the operating lever may be moved through the stroke of movement between the stop pins 57, mounted on the base plate.

A suitable resilient member 58 engages 45 the movable contact plate 49 and serves to hold it in contact with the bearing washer 59, the resilient member 58 being secured as indicated at 60 to one edge portion of the base.

Directly under the resilient member 58 as shown in Figs. 9 and 10, the base plate is formed with a plurality of radially aligned 50 openings 61 which receive a plurality of contact members 62 having end portions 63 formed to extend in inclined relation to the base plate 47 to provide a cam surface for engagement with the movable contact plate. These contact members are formed of resilient wire or other material and having the 55 portions 64 adapted for axial movement

through the opening 61 while the end portion 65 is secured at its free end to the contact or binding post 66. These binding posts are mounted on the upper sides of the base plate as shown in Fig. 11 and arranged 70 adjacent the corner portions thereof.

A coiled spring 67 is mounted on the shaft 48 and has one end anchored in the flange 68 on the end of said shaft while the opposite end is anchored in the operating member 54 so as to normally tend to rotate the contact plate in one direction to hold the operating lever in engagement with one of the stops 57. Upon each operation of the pull chain 56 or other operating member 80 used to move the lever 55 through one stroke to engage the opposite stop 57, the ratchet teeth 53 will cooperate with the teeth 52 on the contact member and rotate said member through one step of movement, 85 which will cause one of the shoulders 51 to engage with its circumferentially aligned contacts 63 and ride on the cam surface thereof so as to slightly depress the contact 62 with which it cooperates to provide an efficient contact to close the circuit controlled thereby.

A suitable nut 69 is mounted on the end of the shaft 48 and provides for a common circuit connection with the shaft in the movable contact plate.

These switch mechanisms as illustrated, are adapted to control a plurality of lamps as indicated at 70 in Fig. 1, so that the circuit to the lamps may be successively closed to light one or more or all of the lamps as desired through the successive operation of the operating member of the switch construction employed such as 14 in Fig. 1, and upon the further operation of which the circuit to all of the lights may be simultaneously opened to extinguish the light or if desired successively broken through the successive operation of the lever 14 by providing a stepped construction similar to the shoulders 7 of the contact body 4 on the opposite ends of the recess or cut away portion 6 formed therein.

A further feature of the invention resides in providing a structure which is inexpensive to manufacture, through the use of the specially constructed block and plate mechanism for the resilient contacts which is adapted to efficiently retain the contact in assembled relation on the base plate and also through the special construction of the movable contact members in either the cylindrical form as shown in Figs. 1 and 6 or in a plate-like form as shown in Fig. 9, together with the simple structure of the operating member used in the several constructions illustrated.

Having thus described my invention, what I claim as new is:

1. A circuit closer comprising a base plate, 120

a shaft mounted on said base plate, a cylindrical contact member rotatably mounted on said shaft having a plurality of offset shoulders, said contact member having a ratchet formed on one end thereof, an annular operating member rotatably mounted on the shaft having a ratchet for cooperation with the ratchet on the contact member, a coiled spring on the shaft normally expansible to move the operating member into engagement with the contact member, and a plurality of resilient strip members secured to the base plate adjacent one end in spaced parallel relation, the opposite end resiliently projecting into the path of movement of the movable contact member and the shoulders thereon.

2. A circuit closer, comprising a base plate, a path having one end mounted in said base plate and projecting laterally therefrom, a contact member rotatably

mounted upon said shaft adjacent said base plate, having a ratchet formed on one end thereof, an operating ratchet member rotatably mounted on said shaft adjacent said contact member and having the ratchet formed thereon adapted for cooperation with the ratchet on the contact member, a coiled spring having one end secured to the end portion of said shaft, and mounted on said shaft with the opposite ends connected with said ratchet member for normally rotating said ratchet member in one direction, means on the base plate for limiting the rotation of the ratchet member by said coiled spring, and a plurality of resilient contact strips mounted in spaced parallel relation on said base plate and projecting into the path of movement of said contact member for circuit closing cooperation, therewith.

In testimony whereof I affix my signature.

CECIL P. BRADLEY.
